UNITED STATES PATENT OFFICE.

HORACE J. MEDBERY, OF BALLSTON, NEW YORK.

MACHINE FOR FORMING SEAMLESS TUBES FROM PULP.

SPECIFICATION forming part of Letters Patent No. 396,103, dated January 15, 1889.

Application filed July 7, 1887. Serial No. 243,638. (No model.)

To all whom it may concern:

Be it known that I, HORACE J. MEDBERY, of Ballston, in the county of Saratoga and State of New York, have invented certain new and useful Improvements in Machines for Forming Seamless Tubes from Pulp, which improvements are fully set forth in the following specification, reference being made therein to the accompanying drawings.

10 My invention relates to machines for making seamless tubes, pipes, or other analogous articles of a uniform diameter throughout from paper or wood pulp; and it consists in the peculiar construction and arrangement of 15 parts adapted to form straight sections of pipe, as hereinafter described.

In the drawings, Figure 1 is a side elevation of the machine embodying my improvements, the former D and its lifting device A being 20 shown nearly at their lowest positions, which lowest positions permit the former to be turned down horizontally, as shown in dotted lines, when freed from the molding-cylinder, the said Fig. 1 also showing in dotted lines the 25 elevated position of the lifter A and attached parts B, C, D, and E as when the former D is fully telescoped into the cylinder L. Fig. 2 is a plan view of the lifter or elevator. Fig. 3 is a sectional view of the upper part of the 30 molding-cylinder with the former in the same. Fig. 4 is a sectional view of the lower part of the same with the former inserted and the parts d and E locked to the bottom of the said molding-cylinder. Fig. 5 is a plan view of the 35 former. Fig. 6 is a perspective view of the former with its different parts partly removed. Fig. 7 is a similar view of the key of the former removed. Fig. 8 is a perspective view of the former and detachable head, the head 40 being partly detached from the main part. Fig. 9 is a detail of a part of the hinge which connects the lower end of the former to the lifter A. Fig. 10 is a plan view of the locking-ring at the bottom of the molding-cylinder.

45 Similar letters refer to similar parts throughout the several views.

A is the lifter or elevator, which is raised by rods K, attached to cross-head I, which latter is forced upwardly by plunger G of hydraulic jack F.

B is the stock-pipe or feeder. C is a portion of the hinge which connects the lower end of the former D to the lifter A, d being the detachable head, with outlets m, Fig. 4, 55 and d² the shaft on which it loosely fits.

E is the locking-ring at the bottom of the molding-cylinder.

L, Figs. 1, 3, and 4, is the hollow molding-cylinder for containing the rubber bag N, into 60 which the former is forced as it ascends, and l, Fig. 3, is the movable plate to which the top of the rubber bag N is secured.

M shows apertures for draining the molding-cylinder L when in operation, m representing the drainage from the former D.

O is the cloth bag that envelops the former, and o is a perforated metallic covering of the main part of the former.

P is the upper end of the former.

p is a gauze or wire netting to allow the discharge of the air from the bag while being filled with pulp, and to admit air into the interior of the former to break the vacuum.

q is the groove or slot, and Q is the key fitting therein.

R is a plate at the top of molding-cylinder, between which and plate l the upper end of rubber bag N is secured.

S, Fig. 3, is the pipe for supplying water 80 under pressure on the outside of rubber bag N.

T is a screw to hold plate R to the top of the molding-cylinder.

W is the base of the molding-cylinder, which has an opening into which passes the head d, 85 and with which opening the stock-pipe B communicates when pulp is to be introduced. This base is provided with hooks w, projecting therefrom, into which fit corresponding parts of the locking-ring E.

X, Fig. 1, is the feed-pipe for the hydraulic jack, by means of which power is applied to raise the former into the molding-cylinder when ready to be charged with pulp.

Y is the key to guide-yoke, Fig. 1.

The former D is a hollow cylinder with a slot for a key running its whole length, its outer surface having circular and longitudinal grooves, at the intersections of which are perforations to allow the passage of air and water. The former D (excepting the slot for key Q) is covered with sheet-brass, o, perforated

for the same purpose, and said sheet-brass is covered with a loose bag or sleeve of cloth, O, which is held tightly in place by key Q, the insertion of which completes the cylinder. 5 Loosely fixed to a post secured to the lower end of said former D is head d, (see Fig. 8,) which may be removed for the purpose of cleaning the former when clogged. Rubber bag N is stationary in molding-cylinder L, 10 and is fastened at the top between plates R l, as before described, or by any other suitable and common means, as will readily be understood. The said bag is fastened to the base of said molding-cylinder by being clamped 15 between base W and its plate above.

Having thus described the construction of my improved machine, I will now explain the mode of its operation.

The former D having been thrown into a 20 perpendicular position, hydraulic pressure is applied at x, whereby the lifter A is raised on the cylinder F. (See Fig. 1). The former D, which is hinged at the lower part to lifter A, is forced up into the elastic rubber bag N, as 25 seen in Fig. 4, and when up its full length within said bag it is locked in position as long as may be desired for charging it with pulp. The pulp or stock is then pumped through the pipe or feeder B, so that the pulp 30 passes in between the former D and rubber bag N until said rubber bag is fully expanded against the inner surface of molding-cylinder L. When sufficient pulp shall have been thus pumped in to fill the space, so that the pulp 35 is tightly pressed between the former D and the rubber bag N, the supply is shut off. Hydraulic pressure is then applied to the exterior of rubber bag N through pipe S, Fig. 3, and the water expressed from the pulp 40 passes through the various grooves or channels cut in the former D and through drainage-outlets at m. The paper-pulp is thus compressed into a tube. Then by means of three-way air-valves (not shown) air is al- 45 lowed to pass into and through the cylinder of former D. This air finds its way through the round holes of the said cylinder and fills the circular and longitudinal grooves thereof, and penetrates the minute openings in the 50 perforated metallic covering o, thus serving to release the pulp now formed into a pipe, so that it will not adhere to the cloth bag en-

veloping the said shaper. When the pressure within molding-cylinder L has been sufficient, by means of a three-way cock at the top (not shown) air is admitted into said cylinder, and the water allowed to pass out by a cock in a pipe communicating with the outlet M at the base of said cylinder. The former D is then unlocked from said cylinder, and air passing 60 up through former D breaks the vacuum between rubber bag N and the newly-formed pipe or tube. The said rubber bag becomes thereby detached from said pipe or tube, and the latter can be withdrawn without injury 65 to either the bag or the article formed. Former D being then withdrawn from molding-cylinder L by an operation the reverse of that by which it was inserted, it is turned down by means of hinge C to a horizontal 70 position. Key Q is then withdrawn, so that cloth bag O becomes slack or loose, and the newly-made pipe or tube may readily be taken off from former D with cloth O.

Having thus fully described my invention, 75 what I claim, and desire to secure by Letters Patent, is—

1. The combination of the molding-cylinder L, having inlet-waterpipe S and outlet waterpipe M, the rubber bag secured at both top 80 and bottom of the cylinder, the adjustable foraminated former D, with detachable head d, having water-outlets m in the same, the rotary adjustable locking-ring E, and the hooks w, substantially as and for the purpose 85 described.

2. The grooved and perforated metal cylinder D, having groove q, the foraminated jacket o, of metal, the outer covering, O, of cloth, and the locking-key Q, fitting in the 90 groove q and securing the said cloth covering, substantially as shown and described.

3. The combination of the hydraulic jack F G, cross-head I, rods K K, attached lifter A, surrounding the jack-cylinder, the molding-cylinder fixed to the upper end of the jack-cylinder, and the foraminated former D, with head d, and the hinge C, for connecting the former to the lifter, with an articulated joint, substantially as shown and described.

HORACE J. MEDBERY.
